UNITED STATES PATENT OFFICE.

PIERRE FONTAN, OF CHICAGO, ILLINOIS.

FASTENER-SETTING IMPLEMENT.

1,149,642.

Specification of Letters Patent. Patented Aug. 10, 1915.

Application filed August 10, 1914. Serial No. 856,102.

To all whom it may concern:

Be it known that I, PIERRE FONTAN, a citizen of the United States, residing in the city of Chicago, county of Cook, and State of Illinois, have invented certain new and Useful Improvements in Fastener-Setting Implements.

The invention relates to means for applying a fastener—to secure together the ends 10 or edges of any soft material.

In the drawings Figure 1 is a perspective view of a wrapped package the ends of which wrapper have been secured by a fastener. Fig. 2 is a side elevation of pliers partly 15 broken away, showing a fastener to be secured therewith. Fig. 3 is a plain view of Fig. 2. Fig. 4 is a top plain view of the fastener. Fig. 5 is a section view showing one application of the fastener secured by 20 the improved device.

Referring to the drawings: A represent a disk of metal having integrals prongs, *a*, punched from the blank: and apertures *a'*.

5 and 6 represent the handles of a pliers 25 pivoted at 7, and having flattened ends for holding and applying a metal fastener. Upon the flattened end of handle 5 is mounted a spring, 9, secured thereto by the rivet, 10, and having free ends, 11, that depend 30 through the aperture, 8.

The flattened end of the handle, 6, terminates in a circular raised portion, having the annular concave groove, 5^a. The disk fastener, A, is applied to the end of the handle, 35 5, by inserting the free ends, 11, of the spring, 9, into the apertures, *a'*, and is held thereto, by reason of lateral pressure of the spring ends upon the disk. The disk fastener being applied to the pliers, the flat-

tened end of the handle, 6, is inserted beneath the parts to be secured together, and pressure applied to the handles, whereby, the prongs, *a*, which extends substantially 40 90 degrees from the body of the metal fastener, will be forced through the material 45 to be united, and coming in contact with the annular groove, 5^a, will be curled back and outwardly through the material and securely unite them to the material in such a manner that the prongs are protected from 50 being tampered with, and a wrapper upon a package is securely fastened without any other agent as twine.

While I have shown a fastener applied to the wrapper ends of a package, by means 55 of the improved setting implement, it is obvious that a fastener can be applied to other purposes by the said fastener setting implement, and I don't limit myself to the precise details of construction except as pointed 60 out in the appended claim.

I claim:

Means for applying a pronged disk having a plurality of spaced apertures; said means comprising a stationary jaw against 65 which the prongs are forced; an apertured movable jaw, having a bearing portion engageable with the marginal portion of the disk, and spaced holding members extending 70 through the aperture in said jaw, and engageable with certain of the apertures in the disk for frictionally holding the disk fastener in position on the movable jaw when said jaws are forced together.

PIERRE FONTAN.
